7 Claims. (Cl. 202—170)

This invention relates to improvements in apparatus for treating metal and like non-absorbent articles with liquids or with the vapors of a solvent which are heavier than air, e. g. with a volatile grease solvent.

Many forms of apparatus have been described for treating metal and like non-absorbent articles with liquids or with solvent vapors, e. g. with a volatile grease solvent both in liquid and in vapor form, whereby grease adhering to the articles may be removed. For treating large quantities of articles, apparatus having automatic conveyors are usually employed, but for apparatus having a small capacity it is more usual to load the goods in a perforated basket or the like which is inserted into and removed from the apparatus by hand; in such cases difficulties frequently arise in treating cup-shaped articles such as shell cases, since it is difficult to avoid removing solvent in at least some of the articles when they are withdrawn and to avoid trapping air in the hollows when they are introduced, thus impeding access of liquid to the whole surface. For many purposes it would be of advantage to have an apparatus incorporating a conveyor suitable for subjecting comparatively small numbers of articles to a single treatment with a grease solvent or solvent vapor and in which cup-shaped articles can be treated without causing them to remove liquid or vapor, as the case may be, when they are withdrawn from the apparatus, or to entrap air when they are introduced.

According to the present invention we provide, in an apparatus for treating metal and like non-absorbent articles with a volatile grease solvent, means for conveying articles through the treating zone comprising a trough, shaped so that its ends extend above the treating zone while the intermediate portion lies within such zone and a travelling chain arranged to pass along a path adjacent to the top of the trough, which chain is provided with members spaced apart along its length and projecting into the trough so as to cause articles placed therein to travel along it.

By this means articles to be treated can be fed into the trough at the end where the chain and the projecting members pass down into the trough, one article being introduced between successive members projecting from the travelling chain. They will then slide on the bottom of the trough down to the intermediate portion within the treating zone, and will then be pushed along by the following member and finally be carried

out of the apparatus. The articles may be fed to the trough separately by hand or by a suitable feed mechanism; similarly they may be removed by hand, or allowed to fall into a receptacle, or on to a travelling band placed appropriately for that purpose. When the articles are submitted in this manner to a treatment with a liquid the members projecting into the trough are preferably perforated to prevent liquid being carried out of the treating zone, and to diminish resistance to the passage through the liquid.

The apparatus may be employed to treat articles with the vapor of a volatile grease solvent and may also be used to spray the articles with solvent, or to treat them with a bath of solvent by arranging for the immediate part for the trough to be immersed in the solvent. In any of the above cases the trough should be provided at its lowest point with an outlet whereby the condensate collecting in the tank can be drained away. Alternatively at least that part of the trough in the treatment zone may be perforated. When treating the articles with a bath of solvent it is also possible to have an imperforate trough, and to use the lower part as the bath container; the vessel in which the trough is located may then act as a reservoir for the liquid. Thus by means of a pump, a circulation of liquid solvent may be set up by which the solvent is delivered from the larger vessel to the trough, and then allowed to overflow the rim of the trough and fall back into the vessel. A thorough washing with a vigorous stream of liquid may thus be attained while the main body of solvent in the vessel will be comparatively quiescent, and any solid particles removed from the treated articles will have an opportunity to settle out.

Preferably a volatile grease solvent is used, the vapors of which are heavier than air, e. g. a chlorinated lower aliphatic hydrocarbon such as trichloroethylene. The apparatus may then, with advantage comprise an open-top tank having in the upper part condensing means around the inside walls to limit upwardly the solvent vapor level, and means for supplying vapor to the lower part. The apparatus may be adapted for vapor treatment only, or for a spray treatment as well. It may also be adapted to treat articles with clean, hot solvent, using the lower part of the trough inside the solvent vapor zone as a liquor bath by feeding condensate to the trough from the condensing means, and allowing solvent to overflow continuously into the tank and thus to the vapor supply means. The latter may be an external still or a sump within the tank. With

this apparatus only a comparatively small volume of solvent is needed although treatment is effected throughout with clean solvent.

One form of our invention, as applied to the treatment of articles with a volatile grease solvent such as trichloroethylene, will now be described with reference to the accompanying diagrams.

In these diagrams:

Fig. 1 represents a sectional elevation of such an apparatus, and

Fig. 2 represents a sectional elevation of part of the apparatus at right angles to Fig. 1 along the line A—A.

In these drawings like numerals represent like parts.

The apparatus comprises an open tank 1 having a bottom 2 sloping down to a sump 3 at one end. In the sump 3 is a steam coil 4 by which solvent in the sump can be vaporised and around the inside of the walls of the tank 1 are disposed condensing coils 5 which can be supplied with water or other cooling liquid by means not shown. These coils are rather more than half-way up the walls, and when in operation will set an upper limit to the vapor zone created by the generation of vapor in sump 3 by causing the vapor to condense on them. A channel 6 is provided around the walls of the tank immediately below coils 5 to catch condensate falling from the coils and deliver it to a receiver 10, and thence to pipe 11, for the purpose to be described hereinafter. To convey articles to be treated through the tank is a trough, U-shaped in section, and formed of a horizontal portion 13 below the level of coils 5, a portion 12 sloping upwards to one end of the tank, and a portion 14 sloping upwards to the other end of the tank: the central portion 13 thus forms with the lower part of portions 12 and 14 a vessel which can be filled with liquid up to the rim of the portion 13. Pipe 11 is arranged to deliver condensate from receiver 10 into this vessel. An endless travelling chain 7 is disposed so that it passes through the apparatus close in turn to the respective portions 12, 13 and 14 of the trough by means of four sprocket wheels 8, 8, 8, 8. There is one sprocket in each of the angles formed by the horizontal portion and the respective sloping portions, and one a short distance above each end of the trough. The lower sprockets run on spindles 15 whose ends are seated in bearings 15' on the inside walls of the tank, while the upper spindles are supported in analogous fashion by means not shown. Alternatively, all four spindles could have been supported by a common frame which in turn could be fixed to the tank, or supported independently of it. In either event, one of the upper sprockets can be driven by a suitable source of power not shown, and the remainder are idle. The endless chain can thus be caused to move in the direction of the arrows.

At intervals along the length of the travelling chains are grid-like members 9 rigidly fixed at right angles to it, so that in that portion of the path of the chain within the apparatus the grids project into the trough. The grids are shaped to occupy the major portion of the cross section of the trough.

The endless chain 7, the grids 9 and the trough into which the latter project together form the means for conveying articles through the apparatus, the inlet being at the upper end 16 of the sloping portion 12, and the exit at the upper end 17 of the sloping portion 14. A chute 18 is pro-

vided by which articles discharged at 17 may be delivered to a suitable destination.

In using the apparatus the horizontal portion 13 of the trough and the sump 3 are filled with solvent, e. g. trichloroethylene. The condensing means are then put into operation, and the solvent in the sump is heated to keep it in steady ebullition. Initially some of the vapor generated will condense on the conveyor and will fall off on to floor 2 and pass thence again into sump 3 but the main portion of the solvent will be condensed on the condensing coils 5, from which it will be delivered, via channel 6, receiver 10, and pipe 11, to the horizontal portion 13 of the trough. The solvent thus delivered to portion 13 will cause solvent already in it to overflow at the rim and fall on to the floor and thus back to sump 3 to be revaporized. A circulation is thus set up whereby fresh solvent is continually being supplied to the bath of solvent in the trough, while little extra solvent is in use beyond that in sump 3.

The endless chain 7 is then put into operation; each grid-like member 9 will in turn pass through the trough. Just after one enters the trough at 16 an article to be treated is inserted at that point by resting it on the grid, and it will then be carried between that grid and the following one down portion 12 in the lower part of which it will receive a short vapor treatment. In the horizontal portion 13 it will be treated with liquid solvent as it is pushed along by the grid immediately behind it, and finally it will pass up sloping portion 14 of the trough when it will dry off in the space above coils 5. On reaching opening 17 it will slide off the grid supporting it and down chute 18 and the grid will travel around again to the other side of the apparatus.

Cup-shaped articles comparable in size (but smaller than) the compartments formed by adjacent grids attached to the conveyor and the trough can be treated satisfactorily by inserting them with the orifice of the "cup" upwards. They will thus pass through the apparatus with this orifice always in the rear. As a result it is assured that air will not be trapped in it and prevent the whole of the interior being reached by the solvent, and moreover that when the article is withdrawn liquid solvent will not be retained but will drain out as the article is moved up out of the horizontal portion of the trough.

Many variations of the invention are possible; for example, spray means may be provided to spray the goods as they leave the bath of solvent. Again, instead of inserting the trough in an enclosing tank, the ends and bottom of the tank may be shaped to form the trough in which the conveyor moves, solvent vapor then being generated in a separate still in communication with the trough-shaped tank. In still further forms of our invention the tank may be closed except for the openings through which the goods are inserted or removed. Again, several troughs, each with its own conveyor, may be provided side by side in the same tank, or a wide trough may be used with a conveyor capable of receiving several articles side by side between successive projecting members.

I claim:

1. Apparatus for treating metal and like non-absorbent articles with a volatile grease solvent, comprising, in combination, a vessel, a solvent degreasing zone in said vessel in which is retained, in both liquid and vaporous state, a volatile grease solvent, and through which articles pass during their treatment in said vessel and de-

greasing zone, means for vaporizing said solvent, additional means for condensing the vaporized solvent when the vaporized material reaches a predetermined level in the degreasing zone of said vessel, means for returning condensate from said condensing means to the portion of the volatile solvent in said degreasing zone which is in liquid state, a trough disposed in said vessel, the extremities of said trough extending above said solvent degreasing zone, while the intermediate portion thereof lies within said degreasing zone, a conveyor arranged to pass along a path adjacent to the top of said trough, said conveyor being provided throughout its length with a plurality of spacedly-disposed, rigidly-mounted members shaped to occupy substantially the major portion of the cross section of said trough, said members during movement of said conveyor being adapted to forcibly charge articles through said trough and said degreasing and condensing zones.

2. Apparatus for treating metal and like non-absorbent articles with a volatile grease solvent comprising, in combination, a vessel, a solvent degreasing zone in said vessel, wherein a volatile grease solvent in both liquid and vaporous state is retained and through which articles pass during treatment in said vessel and zone, means for vaporizing said solvent, further means for condensing the vaporized portion of said solvent when it reaches a predetermined level in the degreasing zone of said vessel, means for passing condensate from said condensing means directly to said degreasing zone, a trough disposed in said vessel and so shaped that its extremities extend above said solvent degreasing zone, while the intermediate portion thereof lies within the degreasing zone, and a traveling chain arranged to pass along a path adjacent to the top of said trough, said chain being provided throughout its length with a plurality of spacedly-arranged grid members rigidly disposed at right angles to said chain and shaped to occupy substantially the major portion of the cross section of said trough, said members being adapted to forcibly charge articles through said trough and said degreasing and condensing zones on movement of said traveling chain.

3. A degreasing apparatus for treating metal and like non-absorbent articles with fluids, comprising in combination a vessel, a treating zone therein in which a volatile grease solvent in liquid and vaporous state is retained and through which articles pass during treatment in said vessel and zone, means for vaporizing said solvent, additional means for condensing the vaporized solvent when the vapors reach a predetermined level in the treating zone of said vessel, means associated with said condensing means for returning condensate to that portion of the solvent which is in liquid state, means for conveying articles through said treating zone comprising a trough shaped so that its ends extend above the treating zone while the intermediate portion lies within it, and a travelling chain arranged to pass along a path adjacent to the top of the trough, which chain is provided with members spaced apart along its length and projecting into the trough so as to cause articles placed therein to travel along it.

4. An apparatus for treating metal and like

non-absorbent articles with a volatile grease solvent comprising in combination a vessel, a solvent degreasing zone in said vessel, in which is retained a volatile grease solvent in both liquid and vaporous state and through which articles pass during treatment in said vessel and zone, means for vaporizing said solvent, additional means for condensing the vaporized solvent when the vapors reach a predetermined level in the degreasing zone, means associated with said condensing means for returning condensate to that portion of the solvent which is in liquid state, a trough shaped so that its ends extend above the solvent degreasing zone while the intermediate portion lies within the said zone, a travelling chain arranged to pass along a path adjacent to the top of the trough, which chain is provided with members spaced apart along its length and projecting into the trough so as to cause articles placed therein to travel along it.

5. An apparatus for treating metal and like non-absorbent articles with a volatile grease solvent comprising in combination a vessel, a treating zone in said vessel wherein a volatile grease solvent in both liquid and vaporous state is retained and through which articles pass during their treatment in said vessel, vaporizing means in the lower part of said vessel for supplying solvent vapor, condensing means in the upper part of said vessel to limit the solvent vapor level and thereby set up a solvent vapor zone, means for passing condensate from said condensing means to that portion of the solvent which is in the liquid state, a trough shaped so that its ends extend to the top of said vessel while the intermediate portion lies within the solvent vapor zone, a travelling chain arranged to pass along a path adjacent to the top of the trough, which chain is provided with members spaced apart along its length and projecting into the trough, so as to cause articles placed therein to travel along it.

6. An apparatus according to claim 5, provided with means for draining solvent from the trough.

7. An apparatus for treating metal and like non-absorbent articles with a volatile grease solvent comprising in combination a vessel, a treating zone in said vessel wherein is retained a volatile grease solvent in both liquid and vaporous condition and through which articles pass during treatment in said vessel and zone, vaporizing means for supplying solvent vapor to the lower part of said vessel, condensing means in the upper part of said vessel to limit upwardly the solvent vapor level and thereby provide a solvent vapor zone, means for passing condensate from said condensing means to the liquid portion of the solvent retained in said treating zone, a trough shaped so that its ends extend above the solvent vapor zone while the intermediate portion lies within the said zone, means for collecting condensate from the said condensing means, means for delivering said condensate to the intermediate portion of the trough, and a travelling chain arranged to pass within the apparatus along a path adjacent to the top of the trough, which chain is provided with members spaced apart along its length and projecting into the trough so as to cause articles placed therein to travel along it.

WALTER F. JESSON.
